(57) **CLAIM**

The ornamental surface design for a pneumatic tire, as shown and described.

DESCRIPTION

FIG. 1 is a perspective view of a pneumatic tire with the ornamental surface design shown thereon;

FIG. 2 is a side view of a pneumatic tire with the ornamental surface design shown thereon;

FIG. 3 is a front view of a pneumatic tire featuring the claimed ornamental surface design; and,

FIG. 4 is an enlarged, partial view of the pneumatic tire of FIG. 1, with the ornamental surface design shown thereon. In the drawings, the broken lines depict environmental subject matter, including environmental subject matter depicting a pneumatic tire, forming no part of the claimed design. The dash-dot-dash lines represent the boundary of the claimed design and form no part of the claimed design.
